UNITED STATES PATENT OFFICE.

JOHN B. DEEDS AND WILLIAM MACK, OF TERRE HAUTE, INDIANA.

WICK-RAISER.

SPECIFICATION forming part of Letters Patent No. 276,525, dated April 24, 1883.

Application filed March 5, 1883. (No model.)

To all whom it may concern:

Be it known that we, JOHN B. DEEDS and WILLIAM MACK, of Terre Haute, in the county of Vigo and State of Indiana, have invented 5 certain new and useful Improvements in Wick-Raisers; and we do hereby declare that the following is a full, clear, and exact description of the invention, which will enable others skilled in the art to which it appertains to 10 make and use the same, reference being had to the accompanying drawings, and to the letters of reference marked thereon, which form a part of this specification.

Our invention has for its object to provide 15 an improved means for raising and trimming the wick in a lantern, miner's lamp, &c.; and to this end it consists in providing the lantern or lamp with a double or single burner, and in arranging therein a double or single hooked-shaped device for raising the wick, said device 20 adapted to be manipulated from the outside of the lamp or lantern by the means arranged thereon, all of which will be more particularly referred to by the accompanying drawings, in which—

Figure 1 is an elevation of a lantern, partly broken away to illustrate the lamp fixed therein, and the means employed for raising the wick, and also in snuffing the flame. Fig. 2 is an 30 elevation of the lamp itself embodying our improvements. Fig. 3 is a view of a double burner, one of the tubes being partly in section, showing the manner in which the wick-raiser works therein; and Fig. 4 is a perspective view 35 of the double or hook shaped prong.

Referring more particularly thereto, A is the lamp, (a being the lantern) representing the common form used in holding oil for railroad-lanterns, and B a double or single tube or burner. 40 The burner in this instance is shown as consisting of two tubular shells, of copper, tin, or other metal, having fitted around them a cup-shaped cap, C, which is screw-threaded for the purpose of screwing it in the top of the lamp. Said cap is soldered to the tubes to retain it 45 thereon, all of this last-described construction being common.

D is a double or single prong shaped device, 50 made of metal or wire, provided on that part which enters the wick-tubes with serrations or teeth for engaging the wick, and it is somewhat prolonged at this portion, so that when

it is left raised it becomes heated for a purpose hereinafter specified. Said prong-shaped device may be of one piece bifurcated and the 55 ends turned up when used with a double burner or may be simply of a single turned-up portion when used with a single burner. The purpose of making it double is to have one serrated end extend up in each tube B, 60 which are each provided with a wick, c, and when pushed up to raise the wick therein. This device D, or rather the longer portion thereof, extends upward on the outside of the double or single burner within the lamp, and is brought through the screw-cap C and bent 65 outward therefrom at right angles, as at e. E is a small rod or wire, which is slightly bent at the lower end, e', to form a catch to enable one to manipulate it. This wire E works in 70 small guides, and a spring, K, soldered or otherwise secured on the outside of the lamp, is provided for the purpose of engaging the crooked portion of said device around the outwardly-turned end e of the wick-raiser, and by pushing it upward elevating the wick. The spring 75 K by its tension serves to retain the rod E at any height at which it may be raised, and prevents looseness and rattling of said rod.

It is well known that in the use of some oils in 80 these lamps—as lard-oil, for instance—in cold weather it freezes and renders hard the feeding of the oil to the wick. We obviate this in the use of our wick-lifter. By keeping the device raised its upper end, g, being thus kept 85 within contact of the flame, becomes heated and imparts some of its heat to the interior of the lamp, thereby preventing the congelation of the oil therein.

F represents a piece of wire arranged on the 90 opposite side of the lamp in a similar manner, and its bent portion e² is made to scrape over the edge of the wicks by twisting it rapidly, and thus trim or take off the charred portions of the wick, this device being of common form. 95 It is common to burn oil in railroad-lanterns, and to such lanterns our invention is particularly adapted. As shown in the drawings, the oil-holder or lamp is provided with the annular rim G and the spring-clips g g for holding it in the lantern. These of course form not part 100 of our invention.

The operation is as follows: When the wick burns down it can readily be raised from the

outside or bottom of the lantern by the manipulation of the wick-raising device through the medium of the wire or rod E, thus obviating the necessity of having to open the lantern 5 and raise the wick through apertures in the sides of the burner with a sharp instrument, or in similar ways, which has heretofore been necessary, and when the wick has become so charred as to not burn well it can be easily or 10 scraped trimmed by the use of the wire F. The rod or wire E can easily be released from its hold around the bent end e of the wick-raiser by simply turning it, and it, together with the device F, can be pushed up in their guides, so 15 not to be struck or affected when the lantern is put down.

It will be seen that by the use of our invention the usefulness of a lantern is widely facilitated and improved.

20 Having thus described our invention, what we claim is—

1. In a lamp for lanterns, the burner having the wick-raiser working therein, an end of which extends up into the said burner and its 25 other end bent to an angle, as described, in combination with the crooked rod E, working in guides on the outside of said lamp and adapted to engage the wick-raiser or to be de-

tached therefrom at will, as and for the purpose described.

2. In a lamp for lanterns, the burner having the wick-raiser, as described, in combination with the crooked manipulating-rod for engaging the same and the guides and spring on the outside of the lamp, said spring being 35 adapted by its tension to keep the rod from falling, as set forth.

3. In a lamp for lanterns, the combination therewith of the wick-raiser and means for lifting the same, as described, said wick-raiser 40 having upwardly-turned teeth on that portion which enters the tube and having plain prolongations beyond said portion adapted to be projected upwardly through the burner and become heated by the flame, whereby the heat 45 imparted thereto is transmitted to the interior of the lamp to prevent congelation of the oil therein, as set forth.

In testimony that we claim the foregoing as our own we hereunto affix our signatures in 50 presence of two witnesses.

JOHN B. DEEDS.
WILLIAM MACK.
